UNITED STATES PATENT OFFICE.

EDWARD GRIEGER, OF PHILADELPHIA, PENNSYLVANIA.

STOP DEVICE FOR TALKING MACHINES.

Application filed April 19, 1920. Serial No. 374,908.

To all whom it may concern:

Be it known that I, EDWARD GRIEGER, a citizen of the United States, residing in Philadelphia, Pennsylvania, have invented a Stop Device for Talking Machines, of which the following is a specification.

My invention relates to stop attachments for phonographs, and one object of my invention is to provide a device for automatically lifting the stylus from the record when the stylus has reached a predetermined point thereon.

A further object is to provide means, operating in conjunction with said stylus elevating-means, whereby the machine is automatically stopped after the stylus has been elevated.

A still further object is to provide means for returning the tone arm and the stylus to a position outwardly of the edge of the record so that the whole device may be made ready for re-starting with a minimum of trouble and delay.

In the attached drawings:

Fig. 1, is a plan view of a phonograph fitted with attachments embodying my invention;

Fig. 2, is a side elevation of a portion of a phonograph embodying my invention, showing the stylus in the playing position;

Fig. 3, is a side elevation similar to that of Fig. 2, showing the stylus elevated above the record;

Fig. 4, is a plan view similar to that of Fig. 1, showing the tone arm in the starting position;

Fig. 5, is a view in perspective of an attachment embodying my invention;

Fig. 6, is a perspective of one form of releasing device;

Fig. 7, is a view in perspective of a record having a modified form of release device attached thereto;

Fig. 8, is a side elevation of a modified form of my device, showing a method of attaching to the tone arm differing from that shown by Fig. 5;

Fig. 9, is a plan view of a phonograph illustrating a still further modification, and showing record equipped with special groove; and

Fig. 10, is a view in side elevation illustrating the modification of Fig. 9.

My invention comprises an automatically actuated member, movable with the tone arm or other movable stylus carrying por-

tion of the machine, and adapted when released to engage the said stylus carrying element and thereby to raise the stylus clear of the record. Coincident with or directly following the elevating of the stylus, an element of the said member is adapted to engage the side of the record supporting carriage whereby the rotary motion of the latter element is utilized to return the tone arm to a position to one side or outwardly of the carriage. The outward movement of the tone arm is limited by a suitable stop, and since the carriage engaging element of the said automatically actuated member continues to engage the said carriage, the movement of the latter is arrested with the stopping of the tone arm.

With reference to the drawings, one form of my device is illustrated in Figs. 1, 2, 3, 4 and 5, and comprises a movable member 1, mounted and adapted to slide longitudinally in suitable bearings 2, 2 upon a bracket member 3, which is adapted to be secured to the tone arm 4 of a talking machine. The said bracket member 3 has, in the present instance, upwardly extending lugs 5, 5 at front and rear, and screws 5^a, 5^a passing through the lugs and into the sound arm 4 hold the said bracket member in place.

An arm 7 extending downwardly from one side of the bracket member has attached thereto a spring 8, said spring being also connected at 9 to the member 1 and tending to move the said member 1 forwardly into an advanced position in the bracket member. At one side of the member 1 is a shoulder 10 which is adapted to engage the rear edge of the forward bearing and to retain the said member in the retracted position against the tension of the spring 8.

The forward end of the member 1 is curved downwardly at 11, and this portion, when the member is released and is carried forward by the spring 8, is adapted to engage, in the present instance, the lower edge of the sound box 12 and to force it upwardly, as clearly shown in Fig. 3, whereby the stylus 13 is raised clear of the record 14 carried upon the rotatable carriage 15 of the talking machine.

In the present instance, I have illustrated the tripping or releasing device associated with the record itself. An arm 16 extends forwardly from the member 1, the outer end of said arm curving downwardly and lying close above the surface of the record

14. Extending through an aperture in the record is a pin or other projection 17, the said aperture being so located in the record that the pin 17 in its rotation will strike 5 and give the arm 16 a lateral thrust whereby the shoulder 10 is released from engagement with the edge of the forward bearing 2, when the stylus has reached the end of 10 the record. The distance of the aperture, through which the pin 17 passes, from the center of the record will, of course, vary 15 in different records, and to accommodate the pin to these varying distances the base 18 which supports the pin is slotted and is 20 adapted to receive in said slot the center pin of the carriage, as shown in Fig. 6, this device being found materially to assist in placing the record on the carriage. The slotted base 18 is made thin and does not prevent the record from lying flat upon the carriage.

Instead of the pin 17, a suitably located shoulder 19 may be formed upon the record, as shown in Fig. 7, or otherwise established, 25 against which the arm 16 is thrust as the tone arm swings inwardly across the record, the tripping of the member 1 thus being accomplished. It is clear that the tripping element may be of any shape and may be 30 permanently secured to the record, or not, as desired.

At the rear of the member 1 is carried a braking element 20, said element, in the present instance, consisting of a downward- 35 ly depending leg 21 upon an arm 22 extending diagonally forward from the member 1. The leg 21 is preferably provided with a rubber buffer 21^a or the like and is adapted when the member 1 is released to engage the 40 side of the rotating carriage, against which it is held by the tension of the spring 8. When the member 1 has been released, with the consequent elevating of the stylus, and the leg 21 has engaged the side of the carriage, continued rotation of the carriage acts 45 to carry the tone arm outwardly over the record to a position clear of the outer edge of the carriage, and a fixed stop 23 located adjacent the carriage and lying in the path 50 of the tone arm is adapted to limit this outward oscillation. The movement of the tone arm thus being stopped, the leg 21 still bearing against the side of the carriage operates as a stop to arrest the rotation of the carriage, whereby the entire mechanism is 55 brought to rest.

In re-starting the machine, the member 1 is re-set in retracted position, an arm 24 being provided upon the member for that purpose, and the stylus again lowered to the record, the carriage having been released with retraction of the member 1.

In Figs. 9 and 10, I have illustrated a modification of my device, in which the arm 60 16 of the member 1 is eliminated and the

shoulder 10 at the forward end of the member 1 replaced by a corresponding shoulder 25, which is adapted to engage the rear edge of the rear bearing 2, as clearly shown in Fig. 9, thus retaining the member 1 in the 70 retracted position against the tension of the spring 8. The releasing device in this modification consists of a vertically disposed arm 26 pivotally secured, in the present instance, to the side of one of the lugs 5 of the bracket member 3, said arm being adapted to engage the side of the member 1 to thrust the said member laterally in the bearings 2 and to release the said shoulder from contact with the edge of the bearing. Normally the arm 75 26 hangs loosely and does not bear against the side of the member 1, but located upon the floor of the phonograph is a stop 27 so placed that when the stylus has advanced to the end of the record, the lower end of the 80 arm 26 comes in contact with the said check, whereupon the arm will be moved around its pivot 26^a and against the side of the member 1, the latter thus being released and moving forward in its bearings to elevate the sound-box in the manner previously 85 described.

In order to insure the arm 26 impinging against the side of the member 1 with sufficient force to release the said member, and to carry the tone arm to the tripping point as quickly as possible after the end of the record has been reached, a steep spiral 28 may be cut in the inner ring of the record, as illustrated in Fig. 9, to receive the stylus 90 after it leaves the regular sound groove, the effect of this spiral being, as stated, to accelerate the movement of the tone arm inwardly toward the stop. Where the spiral is employed, the stop may be set permanently, but where the spiral is dispensed with, the stop 27 may be adjustable upon the floor of the phonograph so that the stopping position may be made to agree exactly with the 95 end of any particular record.

In Fig. 8, I show a modification of the means by which the said device is attached to the tone arm, this form being particularly adapted to phonographs of the type in which the position of the sound-box relative to the tone arm is fixed and which requires the elevation of the major portion of the tone arm as well as the sound-box when the stylus is removed from the record. In this modification, the lugs 5, 5, of the bracket member 3 are eliminated and the said bracket member provided with an extension 29 adapted to be attached to the portion 30 of the tone arm 31, and a strut member 33 is provided upon the bracket member 3, said strut member extending downwardly and bearing against the side of the fixed portion 32 of the sound arm. In this modification, the arm 22 of the member 1 is also eliminated and is replaced by a down- 100 105 110 115 120 125 130

wardly extending arm 34 which carries a buffer 34^a at the lower end thereof, which is adapted to engage the side of the carriage 15 in the same manner as the buffer 21^a.

5 It is clear that this device is capable of modification in a number of ways with no departure from the essential features of the invention, and it will be understood that I do not desire to limit my invention to any 10 particular form or set of forms.

I claim:

1. In a talking machine, the combination with a rotatable carriage adapted to hold a record, of a tone arm carrying a stylus, a 15 member slidably mounted upon and solely supported by the tone arm and having portions adapted respectively for raising the stylus clear of the record and to engage the carriage, a spring tending to shift the member 20 into operating position in which the stylus is elevated by one of said portions and the carriage engaged by the other, means for normally retaining the said member in inoperative position, and means for releasing 25 said member when the stylus has reached a predetermined point upon the record to permit the spring to shift the member into operating position.

2. In a talking machine, the combination 30 with a rotatable carriage adapted to hold a record, of a tone arm carrying a stylus, a member slidably mounted upon the tone arm and having portions adapted respectively to raise the stylus by engagement with the 35 sound box and to engage the carriage, a spring tending to shift the member into sound box and carriage-engaging position, means for releasably retaining the member 40 free from engagement with the sound box and the carriage, and means automatically operative to release the member from the retaining means when the stylus has reached a predetermined point upon the record to permit the spring to shift the member into 45 engagement with the sound box and the carriage.

3. In a talking machine, the combination 50 with a rotatable carriage adapted to hold a record, of a tone arm carrying a stylus adapted to engage the record, a member movably mounted upon the tone arm and having in an operative position one end adapted to elevate the stylus from the record and the other end adapted to engage the carriage, a 55 spring tending to shift the member into operative position, means for retaining the member in inoperative position, means automatically operative when the needle has reached a predetermined position upon the 60 record to release the member to permit the spring to shift it into operative position whereby the stylus is elevated from the record and the tone arm shifted by the movement of the carriage outwardly of the 65 record, and a stop limiting the outward

movement of the tone arm whereby the carriage-engaging end of the member functions to stop the rotation of the carriage.

4. In a talking machine, the combination with a rotatable carriage adapted to hold a record, of a tone arm carrying a stylus, an automatically movable member carried and supported solely by said tone arm and adapted to raise the stylus clear of the record, an element carried by said member 75 for engaging the carriage whereby the tone arm is shifted outwardly of said record, and means supported by the carriage for releasing said member when the stylus has reached a predetermined point upon the said record. 80

5. In a talking machine, the combination with a rotatable carriage adapted to hold a record, of a tone arm carrying a stylus, a member slidably mounted on and supported solely by the tone arm and adapted 85 to raise the stylus clear of the record, said member having an element adapted to engage the side of the carriage following the elevation of the stylus whereby the tone arm is shifted outwardly of the record by the 90 action of the carriage, a stop limiting the outward movement of the tone arm whereby the carriage-engaging element of the member 95 interrupts the rotation of the carriage, and means for releasing said member when the stylus has reached a predetermined point upon the record.

6. In a talking machine, the combination with a rotatable carriage adapted to hold a record, of a tone arm carrying a stylus adapted to engage said record, a member 100 slidably mounted on and supported solely by the tone arm and adapted to raise the stylus clear of the record, a spring tending to shift the member into the stylus-raising position, means for releasably retaining the member in inoperative position, and means supported by the carriage for tripping the retaining means to release the member and to permit movement of said member by the 105 spring into stylus-raising position. 110

7. In a talking machine, the combination with a rotatable carriage adapted to hold a record, of a tone arm carrying a stylus adapted to engage said record, a movable member 115 carried and supported solely by the tone arm and adapted to raise the stylus clear of the record, a spring tending to shift the member into the stylus-raising position, means for releasably retaining the member in inoperative position, and adjustable means supported by the carriage for tripping the retaining means to release the member and to permit movement of said member by the spring into 120 stylus-raising position. 125

8. In a talking machine, the combination with a rotatable carriage adapted to hold a record, of a tone arm carrying a stylus, a movable member carried and supported solely by said tone arm and adapted to raise 130

the stylus clear of the record, a spring for actuating said member to raise the stylus, means normally retaining the member in retracted position, a projection extending 5 above the face of the record and movable therewith, and an extension upon said member adapted to be engaged by the projection when the stylus has reached a predetermined point upon the said record whereby 10 the said member is released from the retaining means and the spring permitted to shift it into the stylus-raising position.

9. A stop attachment for phonographs comprising a bracket member adapted to 15 be attached to the tone arm of the phonograph, a member mounted in the bracket and slidable therein longitudinally of the tone arm, said member being adapted to engage the stylus-carrying member for raising 20 the stylus clear of the record, a spring tending to shift the member into stylus-raising position, a shoulder on said member adapted to engage the bracket member to retain it in retracted position against the tension of 25 the spring, and means for shifting the said

member laterally in the bracket to disengage the shoulder and permit movement of the member by the spring into stylus-raising position.

10. In a talking machine, the combination 30 with a rotatable carriage adapted to hold a record, of a tone arm carrying a stylus, a bracket member adapted to be attached to the tone arm, a member slidably mounted in said bracket member and adapted to engage the stylus-carrying member for raising the stylus clear of the record, an element on 35 said member adapted when the member is in the stylus-raising position to engage the side of the carriage, a spring tending to shift the member into the stylus-raising position, a shoulder on the slidable member adapted to engage the bracket to retain the said member in retracted position against the tension of the spring, and means for shifting the member laterally in the bracket to release the shoulder to permit the spring 40 to shift the member into stylus-raising position.

EDWARD GRIEGER.
